Ues. 1518

John B. Earnshaw of Cincinnati, Ohio.
Letters Patent No. 1518, dated Jan. 21, 1862.

The schedule referred to in these Letters Patent and making part of the same.

To all whom it may concern;

Be it known that I, John B. Earnshaw, of Cincinnati, Hamilton County, Ohio, have invented a new design for a Monument, and I do hereby declare the accompanying drawing making part of this specification, to be a front elevation of the said design.

I claim as new and of my invention.

The Monumental Design represented in the accompanying drawing.

In testimony of which invention I have this day set my hand,

Witness,

Geo. W. Knight,

Jas. Fay.

John B. Earnshaw.
